Claims priority, application France May 20, 1957

14 Claims. (Cl. 8—127.5)

This invention relates to the deformation of keratinous fibers and more especially live human hair. The curling or dekinking of hair is effected by means of compositions, effectiveness of which depends primarily upon the nature of the reducing substances contained therein. More especially, inorganic or organic sulphites, if desired in association with bisulphites, are usually employed. Thiols or mercaptans may also be used, generally in the form of alkali metal salts or ammonium salts.

Difficulties are encountered in applying the aforesaid reducing agents, and more especially since they must be used at clearly defined pH values. Moreover, the odor of mercaptans is somewhat unpleasant and they may produce allergic reactions in persons with whom they come into contact. It has therefore previously been proposed to use, for splitting the cystine linkages of the keratin of the hair, hydrogen-generating reactants consisting of alkali metal borohydrides, preferably as a powder uniformly embedded in a water-miscible, inert carrier as described in copending application, Serial No. 573,618, filed March 26, 1956 (now abandoned).

Such a process of permanently waving hair by means of an aqueous solution of an alkaline borohydride is described in copending application, Serial No. 593,364, filed June 25, 1956 (now abandoned). Although it obviates the disadvantages inherent in the use of sulphites or mercaptans, its application nevertheless requires a fairly strict control of the pH-value of the medium employed, as the basicity of the aqueous borohydride solutions increases along with hydrolysis; this control however is the more so easy as the nature of the composition to be used has been suitably chosen.

Copending application Serial No. 573,618, now abandoned, and application Serial No. 593,364, now abandoned, were combined in a continuation-in-part application and issued as Patent No. 2,963,405.

It is an object of the present invention to provide a new process for the permanent deformation of keratinous fibers and more particularly of human hair at room temperature in a simple and reliable manner and within a reasonable time and which obviates or minimizes all the aforesaid difficulties.

According to the present invention there is provided a process for the deformation of keratinous fibers, particularly live human hair, which comprises applying to the hair or other fibers, before and/or after constraining the hair or other fibers into a desired configuration, an aqueous solution adjusted to a pH-value of 9-10 comprising at least one water-soluble sulphite of alkaline reaction and sodium and/or potassium borohydride, in the proportion of one mole of sulphite to 1-20 moles (preferably, 2-4 moles) of borohydride, the total quantity of the reducing agents employed being such that the concentration of active hydrogen theoretically available is not more than 2 grams per 100 cc. of the aqueous-reducing composition, allowing said composition to act on the hair for at least 15 minutes and thereafter rinsing, fixing and drying the hair.

The concentration of theoretically available active hydrogen as referred to above is calculated from the following equations:

which shows that the reducing power of one mole of an alkali metal borohydride MeBH_4 (wherein Me is the alkali metal) is theoretically four times that of one mole of an alkali metal sulphite Me_2SO_3 when the reducing power is calculated in gram-atoms of active hydrogen.

Whilst the invention is not to be regarded as restricted to any theoretical explanation of reduction of the disulphide bridges of keratin or, more generally, with regard to the softening action exerted on the hair by such mixtures of sulphite and borohydride, it is believed possible that the sulphite, in the presence of the keratin of the hair, the borohydride and probable by-products of the reaction, constitutes a "redox" system, that is to say functions as an intermediate between the borohydride and the keratin. In this way the waste of borohydrides as a result of the evolution of nascent hydrogen and the rapid elimination of the latter by conversion into molecular hydrogen, such as occurs when a borohydride is used as a sole reducing agent, is avoided. Due to the presence of sulphite, the whole of the reducing power of the composition is as it were conveyed to the hair through the non volatile compounds such as the sulphite and other related reducing agents which derive thereof and which contain sulphur in a vicinal oxidation stage. In an intentionally simplified example, it may be assumed that a quantity of sulphite reduces the keratin with concomitant conversion into sulphate and that this sulphate is instantaneously reduced back to sulphite by the nascent hydrogen of the borohydride, and so on. What actually happens is probably more complex, especially in view of the many oxidation stages where sulphur may be, at least theoretically (sulphites, hydrosulphites, thiosulphates, sulphides, etc.).

It has been found that if the softening of hair is effected 40 by means of an aqueous composition containing both a sulphite and a borohydride in the proportions indicated above, there is finally obtained, in a shorter period of treatment, a curl which is tighter and more attractive than that obtained by means of either one of these reactants when used alone. The effect obtained is all the more surprising in that it is superior to the sum of the effects of these two reducing agents used separately. In particular, it has been found that the reducing action of the mixture of sulphite and borohydride manifests itself immediately on application, whereas with an aqueous solution containing only a borohydride, even if this solution is adjusted to a favourable pH value (9 to 10) for a steady decomposition, there is an initial, latent period during which the reducing action is negligible.

In accordance with a further feature of the invention, 55 penetrating and/or swelling agents, known per se for improving the effectiveness of the conventional preparations for permanent waving, are added to the composition. In this way an even more complete and effective utilization of the reducing properties of the sulphite-borohydride association is obtained. The improvement thus afforded is much greater than that resulting from the addition of these same penetration and/or swelling agents to a composition containing solely sulphites or solely borohydrides.

The process according to the invention for effecting the 60 permanent deformation of hair is thus definitely more effective than the known processes in which only sulphites or borohydrides are employed. Apart from the particularly marked results obtained in practice, this superiority has been verified by taking as a basis of comparison the percentage of the cystine linkages being split as a function of the duration of contact. This percentage

was determined photo colorimetrically by the method of Folin et al. by means of phospho-tungstic acid (J. Biol. Chem., vol. 112 (1935), p. 683, and Bulletin de l'Institut Textile de France, vol. 30 (1952), pp. 255-271). The tests were carried out on hairs of medium texture taken from a same subject, shampooed, rinsed and dried. Each test consists of treating one tress weighing 1.25 g. with 5 cc. of reducing solution at a temperature of 20° C. for 20 minutes. The compositions of the solutions employed in each of these tests, in which the proportions are expressed in grams per 100 cc. of solution, are as follows:

Test	A	B	C	D	E	F
Test A:						G.
Sodium sulphite						2
Glycine						2
Water to make 100 cc.						
Test B:						2
Sodium borohydride						2
Glycine						2
Water to make 100 cc.						
Test C:						2
Sodium sulphite						2
Sodium borohydride						2
Glycine						2
Water to make 100 cc.						
Test D:						2
Sodium sulphite						2
Glycine						2
Urea						12
Ethanol						15
Water to make 100 cc.						
Test E:						2
Sodium borohydride						2
Glycine						2
Urea						12
Ethanol						15
Water to make 100 cc.						
Test F:						2
Sodium sulphite						2
Sodium borohydride						2
Glycine						2
Urea						12
Ethanol						15
Water to make 100 cc.						

It will be noted that in all these tests, involving the same sulphite and the same borohydride merely with a view to facilitating the comparison, the same reactant was chosen for the adjustment of the pH i.e. glycine, and the same proportion of the same penetrating and swelling agents for promoting the reducing action, namely 15% ethanol and 12% urea. Naturally, while these products and the proportions thereof as indicated do in fact give satisfactory results under the aforesaid conditions, the invention is not to be considered as limited to them in any way.

The results of the aforementioned tests have been included in the following table, which sets out the percentage of cystine linkages being split by the two reducing agents employed, separately and in mixture, at suitable concentrations.

TABLE

Test	A	B	C	D	E	F
Initial pH	9.0	9.1-9.2	9.2	9.3	9.1-9.2	9.3
Reduction, Percent	1.5	1.4	13	1.5	1.6	18.8
(Extreme values measured)	0.9	1.1	10.3	1.2	1.5	16
Penetrating and swelling agents				15% ethanol and 12% urea		

This table clearly shows that mixtures of the two reducing agents (tests C and F) exert a much greater reducing action than the sum of their reducing actions when used alone (A+B or D+E). Moreover, it shows that under substantially the same conditions of initial pH-

values (9.0 to 9.3, i.e. moderately alkaline as compared with the usual methods of cold-waving), the addition of penetrating and swelling agents, such as ethanol and urea, does not substantially improve the action of the sulphite or borohydride when used separately as reducing agents (compare the reduction percentages in columns D and E of the table with those in columns A and B), but does very substantially increase the efficacy of the mixture of the two reducing agents (compare the reduction percentage in column F of the table with that in column C).

Suitable water-soluble sulphites having an alkaline reaction for use in the process of the present invention are, for example, sodium sulphite, potassium sulphite and the sulphites of nitrogenous organic bases, such as triethanolamine sulphite, morpholine sulphite and guanidine sulphite.

In effecting control of the pH-value of the solutions, it was found preferable to resort to buffers or compounds, such as weak acids, which are capable under the conditions in which they are employed of forming buffered systems. These include, for example, boric acid alone or mixed with calcium chloride, tartaric acid, citric acid, lactic acid, di-hydrogen ortho-sodium phosphate, glycine, sarcosine and taurine. It has also been found that it may be advantageous to start the treatment in the presence of a small quantity of the weak acid and to add a further quantity of the same acid in the course of the treatment, by spraying or by any other suitable means.

The agents promoting the penetration of the reactants into the hair, and the use of which has proved advantageous for carrying out the process according to the invention, include those already proposed for permanent waving by means of sulphites, especially lower alcohols, such as ethanol and isopropanol, the glycols and the ethers or esterethers of glycols, such as ethylene-glycol, diethylene-glycol, the monoethyl and monobutyl ethers of ethylene-glycol, the acetate of ethyleneglycol monoethyl ether, and cyclic ethers such as dioxane or dioxolane. One particularly advantageous method of carrying out the present invention consists in preparing the aqueous composition by dissolution of a mixture obtained in accordance with the process described in application Ser. No. 573,618 and wherein the binder or carrier for the borohydride powder also acts as a penetrating agent. An example of such a binder is a polycondensate of ethylene oxide, such as the product known under the registered trademark "Carbowax 1540".

The invention further includes a hair treating composition suitable for carrying out the process according to the invention this composition comprising a pulverulent mixture of a water-soluble sulphite of alkaline reaction, sodium and/or potassium borohydride and a crystalline weak acid, all uniformly embedded as a stable dispersion in a solid, fusible and water-miscible carrier which is chemically inert under normal conditions of storage and use, said composition containing one mole of sulphite to 1-20 moles (preferably, 2-4 moles) of borohydride. Such a composition can be prepared for example according to the process described in application Ser. No. 573,618.

The hair-swelling agents which have already been proposed for permanent waving and which may advantageously be employed in carrying out the process according to the present invention include, for example, urea, thiourea, formamide and acetamide.

The process according to the invention is equally suitable for smoothing kinky hair and for permanently waving straight hair by the usual techniques. In permanent waving, the hair tresses are wound on curlers of suitable shape and dimensions. These tresses are impregnated with the reducing solution immediately before and/or after they are wound. The solution is then allowed to act for a period of time necessary for the softening of the hair, generally 15 to 45 minutes, and the hair is then rinsed and fixed in the usual manner, for example by

means of dilute hydrogen peroxide or an aqueous sodium bromate solution, after which the locks can be unwound from the curlers and dried. It is also possible simply to rinse the locks by means of a dilute solution of a weak organic acid, such as lactic acid or citric acid, and to allow the reoxidation to take place by itself under the action of the oxygen of the ambient air. The period of contact of the reducing solution varies in accordance with the nature of the hair treated and in accordance with the concentration of the reactants. A period from 20 to 25 minutes is generally sufficient. Of course, if the operation is carried out with a relatively high concentration of reducing agent, particularly of borohydride, care should be taken that the duration of contact is sufficiently short to avoid any hydrolysis of the keratin.

The following examples will serve to illustrate the invention:

Example I

Live hair, previously wound on curlers, is impregnated with a solution having the following composition:

	G.
Sodium borohydride	4.8
Anhydrous sodium sulphite	2.4
Glycine	0.1
Water to make 100 cc.	

After 20 minutes, the hair is rinsed and fixed by means of a 3% aqueous solution of hydrogen peroxide. A curl of medium tightness is obtained.

Example II

Live hair of medium texture, previously wound on curlers, is treated with a solution having the following composition:

	G.
Sodium borohydride	2
Anhydrous sodium sulphite	2
Taurine	1
Ethanol	15
Urea	12
Water to make 100 cc.	

The pH-value of this solution is 9.5. After 25 minutes have elapsed, the hair is rinsed and treated with a 3% aqueous solution of hydrogen peroxide. A satisfactory curl is obtained.

Example III

Fairly coarse live hair, previously wound on curlers, is impregnated with a solution having the following composition:

	G.
Sodium borohydride	3
Anhydrous sodium sulphite	3
Glycine	3
Ethanol	15
Urea	12
Water to make 100 cc.	

The solution, which has a pH-value of 9.5, is left in contact with the hair for 15 minutes, whereafter the hair is rinsed and fixed in the usual manner by means of dilute hydrogen peroxide. A durable curl of medium tightness is obtained.

Example IV

Fairly coarse, dry hair is treated with a solution having the following composition:

	G.
Sodium borohydride	2
Anhydrous sodium sulphite	1
Ethanol	15
Urea	12
Water to make 100 cc.	

After 25 minutes, the hair is rinsed and fixed by means of dilute hydrogen peroxide. A tight curl is obtained.

Example V

Fairly fine and slightly greasy live hair is impregnated, after having been wound on curlers, with a solution having the following composition:

	G.
Sodium borohydride	3
Anhydrous sodium sulphite	0.5
Glycine	0.1
Lactamidopiperidine	10
Ethylene-glycol monobutyl ether	10
Water to make 100 cc.	

The hair is covered with a close-fitting cap. After 20 minutes, it is rinsed, fixed and dried. A satisfactory curl of medium tightness is obtained.

Example VI

A solution of the following composition is applied to hair wound on curlers:

	G.
Sodium borohydride	3
Anhydrous sodium sulphite	3
Glycine	3
Ethanol	15
Urea	12
Water to make 100 cc.	

The initial pH-value is 9.4. After 15 minutes, the hair is rinsed, fixed and dried. A fairly tight, durable curl is obtained.

Example VII

Live hair is wound on curlers and impregnated with a solution having the following composition:

	G.
Sodium borohydride	2
Anhydrous sodium sulphite	2
Boric acid	1
Ethanol	15
Urea	12
Water to make 100 cc.	

The initial pH-value is equal to 9.3. After a period of contact of 30 minutes, the hair is rinsed, fixed by means of dilute hydrogen peroxide and dried. A stable curl of medium tightness is obtained.

Example VIII

Dry hair of medium texture is treated with a solution having the following composition:

	G.
Sodium borohydride	2
Sodium metabisulphite	3
Glycine	2
Water to make 100 cc.	

The pH of this solution is 9.2. The hair is immediately wound on curlers and the impregnation is completed with the same solution. After a period of contact of 20 minutes, the hair is rinsed, fixed by means of a dilute hydrogen peroxide solution, unwound and dried. A satisfactory, somewhat loose curl is obtained.

Example IX

The procedure of Example VIII is followed, but a solution having the following composition is employed

	G.
Sodium borohydride	2
Sodium metabisulphite	3
Glycine	2
Ethanol	15
Urea	12
Water to make 100 cc.	

The pH-value of this solution at the time of application is 9.5. After rinsing, fixing and drying, a satisfactory curl is obtained, which is somewhat tighter than that obtained in the preceding example.

Example X

Rather fine live hair is impregnated with a solution having the following composition:

	G.
Sodium borohydride	3
Anhydrous sodium sulphite	3
Glycine	1.5
Ethanol	15
Urea	12
Water to make 100 cc.	

The hair is immediately wound on curlers. After a period of contact of 10 minutes, a solution of 1.5 g. of glycine in 20 cc. of water is sprayed onto the hair. After a further 10 minutes, the hair is rinsed with water, fixed with a 2% hydrogen peroxide solution and dried. A tight and durable curl is obtained.

What we claim is:

1. A method of permanently reshaping human hair and other keratinous fibers which comprises holding the fibers in desired shape while they are wetted with a hair-softening solution adjusted to a pH-value within the range of about 9.0 to 10.0 and containing at least one water-soluble sulphite and at least one alkali metal borohydride of a molecular weight higher than 35 in a ratio of one mole of sulphite to 1-20 moles of borohydride, the total quantity of both reactants being such as to amount to a concentration of active hydrogen theoretically available of not more than 2 grams per 100 cc. of the hair-softening solution, allowing said solution to remain in contact with the fibers for at least 15 minutes, and thereafter rinsing, setting by treating with an oxidizing agent, releasing and drying the fibers.

2. A method of permanently reshaping human hair and other keratinous fibers according to claim 1, wherein the water-soluble sulphite and the alkali metal borohydride are used in a ratio of one mole of sulphite to 2-4 moles of borohydride.

3. A method of permanently reshaping human hair and other keratinous fibers which comprises holding the fibers in desired shape while they are wetted with a hair-softening solution buffered to a pH-value within the range of about 9.0 to 10.0 and containing at least one water-soluble sulphite and at least one alkali metal borohydride of a molecular weight higher than 35 in a ratio of one mole of sulphite to 1-20 moles of borohydride, the total quantity of both reactants being such as to amount to a concentration of active hydrogen theoretically available of not more than 2 grams per 100 cc. of the hair-softening solution, allowing said solution to remain in contact with the fibers for at least 15 minutes, and thereafter rinsing, setting by treating with an oxidizing agent, releasing and drying the fibers.

4. A method of permanently reshaping human hair and other keratinous fibers which comprises holding the fibers in desired shape while they are wetted with a hair-softening solution initially adjusted to a pH-value within the range of about 9.0 to 10.0 and containing at least one water-soluble sulphite and at least one alkali metal borohydride of a molecular weight higher than 35 in a ratio of one mole of sulphite to 1-20 moles of borohydride, the total quantity of both reactants being such as to amount to a concentration of active hydrogen theoretically available of not more than 2 grams per 100 cc. of the hair-softening solution, allowing said solution to remain in contact with the fibers for at least 15 minutes at ambient temperature while the pH is maintained at the desired value by addition of a compound selected from the class consisting of boric acid, tartaric acid, lactic acid, citric acid, glycine, sarcosine and taurine, and thereafter rinsing, setting by treating with an oxidizing agent, releasing and drying the fibers.

5. A method of permanently reshaping human hair and other keratinous fibers which comprises holding the fibers

in desired shape while they are wetted with a hair-softening solution adjusted to a pH-value within the range of about 9.0 to 10.0 and containing at least one sulphite selected from the class consisting of sodium sulphite, potassium sulphite, lithium sulphite, sodium metabolysulphite, potassium metabolysulphite and sulphites of nitrogenous organic bases and at least one alkali metal borohydride of a molecular weight higher than 35 in a ratio of one mole of sulphite to 1-20 moles of borohydride, the total quantity of both types of reactants being such as to amount to a concentration of active hydrogen theoretically available of not more than 2 grams per 100 cc. of the hair-softening solution, allowing said solution to remain in contact with the fibers for at least 15 minutes at ambient temperature, and thereafter rinsing, setting by treating with an oxidizing agent, releasing and drying the fibers.

6. A method for permanently reshaping human hair and other keratinous fibers which comprises holding the fibers in desired shape while they are wetted with a hair-softening solution adjusted to a pH-value within the range of about 9.0 to 10.0 containing at least one water-soluble sulphite, at least one alkali metal borohydride of a molecular weight higher than 35 in a ratio of one mole of sulphite to 1-20 moles of borohydride and a penetration agent selected from the class consisting of lower fatty alcohols, glycols, glycol ethers, glycol ether-esters, cyclic ethers and ethylene oxide polycondensates, the total quantity of the reducing agents being such as to amount to a concentration of active hydrogen theoretically available of not more than 2 grams per 100 cc. of the hair-softening solution, allowing said solution to remain in contact with the fibers for at least 15 minutes at ambient temperature, and thereafter rinsing, setting by treating with an oxidizing agent, releasing and drying the fibers.

7. A method of permanently reshaping human hair and other keratinous fibers which comprises holding the fibers in desired shape while they are wetted with an aqueous hair-softening solution adjusted to a pH-value within the range of about 9.0 to 10.0 containing at least one water-soluble sulphite, at least one alkali metal borohydride of a molecular weight higher than 35 in a ratio of one mole of sulphite to 1-20 moles of borohydride and a hair-swelling agent selected from the class consisting of urea, thiourea, formamide, acetamide and carboxylic acid amides of organic heterocyclic nitrogenous bases, the total quantity of the reducing agents being such as to amount to a concentration of active hydrogen theoretically available of not more than 2 grams per 100 cc. of the hair-softening solution, allowing said solution to remain in contact with the fibers for at least 15 minutes at ambient temperature, and thereafter rinsing, setting by treating with an oxidizing agent, releasing and drying the fibers.

8. A method of permanently reshaping human hair and other keratinous fibers which comprises holding the fibers in desired shape while they are wetted with an aqueous hair-softening solution adjusted to a pH-value within the range of about 9.0 to 10.0 containing at least one water-soluble sulphite, at least one alkali metal borohydride of a molecular weight higher than 35 in a ratio of one mole of sulphite to 1-20 moles of borohydride, the total quantity of the reducing agents being such as to amount to a concentration of active hydrogen theoretically available of not more than 2 grams per 100 cc. of the hair-softening solution, allowing said solution to remain in contact with the fibers for at least 15 minutes at ambient temperature, rinsing the fibers with a dilute aqueous solution of a weak organic acid, setting them by exposure to ambient air and finally drying them.

9. In a method of permanently reshaping human hair and other keratinous fibers by holding the fibers in desired shape while they are wetted with an aqueous hair-

softening solution adjusted to a pH-value within the range of about 9.0 to 10.0 containing at least one water-soluble sulphite, at least one alkali metal borohydride of a molecular weight higher than 35 in a ratio of one mole of sulphite to 1-20 moles of borohydride and an acid compound selected from the class consisting of boric acid, tartaric acid, lactic acid, citric acid, glycine, sarcosine and taurine, the total quantity of the reducing agents being such as to amount to a concentration of active hydrogen theoretically available of not more than 2 grams per 100 cc. of the hair-softening solution and the time allowed for said solution to remain in contact with the fibers being of at least 15 minutes at ambient temperature, the step which comprises keeping apart substantially half the amount of said acid compound and applying it to the fiber about 10 minutes later.

10. A method of permanently reshaping human hair and other keratinous fibers which comprises holding the fibers in desired shape while they are wetted with an aqueous hair-softening solution buffered to a pH-value within the range of about 9.0 to 10.0 containing at least one water-soluble sulphite, at least one alkali metal borohydride of a molecular weight higher than 35 in a ratio of one mole of sulphite to 1-20 moles of borohydride, a water miscible penetrating agent selected from the class consisting of lower fatty alcohols, glycols, glycol ethers, glycol ether-esters, cyclic ethers and ethylene oxide polycondensates and a water soluble hair swelling agent selected from the class consisting of urea, thio-urea, formamide, acetamide and carboxylic acid amides of organic heterocyclic nitrogenous bases in an aqueous medium, the total quantity of the reducing agents being such as to amount to a concentration of active hydrogen theoretically available of not more than 2 grams per 100 cc. of the hair-softening solution, allowing said solution to remain in contact with the fibers for at least 15 minutes at ambient temperature, and thereafter rinsing, setting by treating with an oxidizing agent, releasing and drying the fibers.

11. A solid hair waving composition to be used in aqueous solution which comprises a pulverulent mixture of a water-soluble sulphite, an alkali metal borohydride of a molecular weight higher than 35 and a crystalline weak acid, all uniformly embedded as a stable dispersion

in a solid, fusible and water-miscible carrier which is chemically inert under normal conditions of storage and use, said composition containing one mole of sulphite to 1-20 moles of borohydride and a suitable amount of the weak acid to ensure a pH-value of 9-10 in the solution ready for use.

12. A solid hair waving composition according to claim 11 wherein the solid, fusible and water-miscible carrier is present in the proportion of at least 50 percent of the composition.

13. A solid hair waving composition to be used in aqueous solution which comprises a pulverulent mixture of a water-soluble sulphite, an alkali metal borohydride of a molecular weight higher than 35 and a crystalline weak acid, all uniformly embedded as a stable dispersion in a waxy polycondensate of ethylene oxide, said composition containing one mole of sulphite to 1-20 moles of borohydride and a suitable amount of the weak acid to ensure a pH-value of 9-10 in the solution ready for use.

20 14. A solid hair waving composition to be used in aqueous solution which comprises a pulverulent mixture of a water-soluble sulphite, an alkali metal borohydride selected from the class consisting of sodium borohydride and potassium borohydride and a crystalline weak acid, all uniformly embedded as a stable dispersion in a polycondensate of ethylene oxide of an average molecular weight higher than 1500, said composition containing one mole of sulphite to 2-4 moles of borohydride and a suitable amount of the weak acid to ensure a pH-value of 9-10 in the solution ready for use.
